COMBINED BICYCLE RADIO AND LIGHT

Jerome L. Pinsler, Evanston, and Anson Isaacson, Chicago, Ill., assignors to Marvin Glass & Associates, Chicago, Ill.

Filed Sept. 4, 1974, Ser. No. 502,926

Term of patent 14 years

Int. Cl. D14—03

U.S. Cl. D56—4 R

FIG. 1 is a rear, top and left side perspective view of a combined bicycle radio and light showing our new design;

FIG. 2 is a top plan view;

FIG. 3 is a left side elevational view, the right side being a mirror image thereof;

FIG. 4 is a bottom plan view;

FIG. 5 is a rear elevational view; and

FIG. 6 is a front elevational view.

We claim:

The ornamental design for a combined bicycle radio and light, as shown and described.
